(57) **CLAIM**

I claim, the ornamental design for an elongated guide wire for medical use, as shown and described.

DESCRIPTION

FIG. 1 is a front view of the guide wire;

FIG. 2 is a right side 45 degree from the front view of the guide wire;

FIG. 3 is a left side 45 degree from the front view of the guide wire;

FIG. 4 is a rear view of the guide wire;

FIG. 5 is a right side 45 degrees from the rear view of the guide wire;

FIG. 6 is a left side 45 degrees from the rear view of the guide wire;

FIG. 7 is a right side view of the guide wire; and,

FIG. 8 is a left side view of the guide wire.

1 Claim, 8 Drawing Sheets
